(57) **CLAIM**

The ornamental design for a touch bin, as shown and described.

DESCRIPTION

FIG. 1 is a front elevational view of the touch bin according to my new design,

FIG. 2 is a top plan view thereof;

FIG. 3 is a right side elevational view thereof;

FIG. 4 is a left side elevational view thereof;

FIG. 5 is a rear elevational view thereof; and,

FIG. 6 is a bottom plan view thereof.

The uniform broken lines shown in the drawings illustrate portions of the touch bin that form no part of the claimed design.
